(57) **CLAIM**

The ornamental design for a headphone, as shown.

DESCRIPTION

FIG. 1 is a perspective view of a first embodiment of a headphone showing our new design;

FIG. 2 is a front elevational view thereof;

FIG. 3 is a rear elevational view thereof;

FIG. 4 is a left side elevational view thereof;

FIG. 5 is a top plan view thereof; and

FIG. 6 is a bottom plan view thereof.

FIG. 7 is a perspective view thereof wherein the headphone housing is in a first alternate position;

FIG. 8 is a perspective view thereof wherein the headphone housing is in a second alternate position;

FIG. 9 is a perspective view thereof wherein the headphone housing is in a third alternate position;

FIG. 10 is a perspective view thereof wherein the headphone housing is in a fourth alternate position;

FIG. 11 is a rear elevational view thereof wherein the headphone housing is in the first alternate position;

FIG. 12 is a rear elevational view thereof wherein the headphone housing is in the second alternate position; and
FIG. 13 is a rear elevational view thereof wherein the headphone housing is in the third alternate position.

FIG. 14 is a rear elevational view thereof wherein the headphone housing is in the fourth alternate position.

FIG. 15 is a perspective view of a second embodiment of a headphone showing our new design;

FIG. 16 is a front elevational view thereof;

FIG. 17 is a rear elevational view thereof;

FIG. 18 is a left side elevational view thereof;

FIG. 19 is a top plan view thereof; and

FIG. 20 is a bottom plan view thereof.

FIG. 21 is a perspective view thereof wherein the headphone housing is in a first alternate position;

FIG. 22 is a perspective view thereof wherein the headphone housing is in a second alternate position;

FIG. 23 is a perspective view thereof wherein the headphone housing is in a third alternate position;

FIG. 24 is a perspective view thereof wherein the headphone housing is in a fourth alternate position;

FIG. 25 is a rear elevational view thereof wherein the headphone housing is in the first alternate position;

FIG. 26 is a rear elevational view thereof wherein the headphone housing is in the second alternate position;

FIG. 27 is a rear elevational view thereof wherein the headphone housing is in the third alternate position; and

(Continued)

FIG. 28 is a rear elevational view thereof wherein the headphone housing is in the fourth alternate position.
 FIG. 29 is a perspective view of a third embodiment of a headphone showing our new design;
 FIG. 30 is a front elevational view thereof;
 FIG. 31 is a rear elevational view thereof;
 FIG. 32 is a left side elevational view thereof;
 FIG. 33 is a top plan view thereof; and
 FIG. 34 is a bottom plan view thereof.
 FIG. 35 is a perspective view thereof wherein the headphone housing is in a first alternate position;
 FIG. 36 is a perspective view thereof wherein the headphone housing is in a second alternate position;
 FIG. 37 is a perspective view thereof wherein the headphone housing is in a third alternate position;
 FIG. 38 is a perspective view thereof wherein the headphone housing is in a fourth alternate position;
 FIG. 39 is a rear elevational view thereof wherein the headphone housing is in the first alternate position;
 FIG. 40 is a rear elevational view thereof wherein the headphone housing is in the second alternate position;
 FIG. 41 is a rear elevational view thereof wherein the headphone housing is in the third alternate position; and
 FIG. 42 is a rear elevational view thereof wherein the headphone housing is in the fourth alternate position.
 FIG. 43 is a right side elevational view of the embodiment of FIG. 1;
 FIG. 44 is a right side elevational view of the embodiment of FIG. 15; and,
 FIG. 45 is a right side elevational view of the embodiment of FIG. 29.
 The broken lines illustrating unclaimed portions of the headphone form no part of the claimed design. Dot-dash broken lines illustrating boundaries of the claimed design form no part of the claimed design.
